UNITED STATES PATENT OFFICE.

NAPOLEON DU BRUL, OF CINCINNATI, OHIO, ASSIGNOR TO MILLER, DU BRUL & PETERS MANUFACTURING COMPANY, OF SAME PLACE.

CIGAR-MOLD.

SPECIFICATION forming part of Letters Patent No. 230,535, dated July 27, 1880.

Application filed May 3, 1880. (No model.)

To all whom it may concern:

Be it known that I, NAPOLEON DU BRUL, of Cincinnati, Hamilton county, Ohio, have invented a new and useful Improvement in Cigar-Molds, of which the following is a specification.

My invention is designed as an improvement in the class of cigar-mold plungers represented in the subject-matter of Patent No. 10 125,005, granted to John Baxter, March 26, 1872, and in which the plungers consist of a strip of metal composing the curb or margin which surrounds a wooden central portion or filling.

In my improvement the metallic shell, curb, or casing is of sheet metal, usually tinned sheet-iron, which is bent around the wooden matrix or body of the plunger, and has flanges preferably inbent and driven into grooves, kerfs, or creases in the body. The ends of the 20 strip of metal composing the curb are bent around the butt-end of the body, and are either secured by solder or by being nailed to the body.

Several modifications will be described in 25 the sequel.

In the accompanying drawings, Figure 1 is a transverse section of a few molds embodying my invention. Fig. 2 shows one of my marginal or curb strips detached. Fig. 3 30 shows, by transverse section, a number of modifications of my invention.

A represents a portion of the lower member of a multiplex cigar-mold, and may be composed, as usual, of wood, and of the customary form.

B are wooden body-pieces or fillings of my plungers, glued or otherwise attached to back C, and being grooved at b to receive the in-turned flanges d of a strip of sheet metal, D, 40 which constitutes the margin, curb, or shell of the plunger.

The inturned edges being cut and bent to

form the flanges d, the latter are forced or driven into the grooves or kerfs b in the body, and the strip itself being bent around the 45 body, its overlapping ends d' are secured by a tack or solder to the butt-end of the body.

At w x y z are represented modifications of my composite plunger.

At w, the metallic casing being flangeless, 50 its upper edges are made to enter and occupy kerfs b" in the body-flanges b'. For additional security, the casing may be sprigged or punch-pricked to the body, as at d".

In the form shown at x the body and its 55 flange back piece, being separate, are excavated, one or both, to receive the inturned flanges of the casing, and are glued or sprigged together and to the back board.

Forms y and z show outturned flanges d'" 60 fastened to the casing, which is secured to the body either by prick-punching, as at y, or by sprigs, as at z.

I claim as new and of my invention—

1. A cigar-mold whose upper matrix or plunger is composed of a wooden body, B, incased by a sheath or curb-strip, D, of sheet metal, whose upper edges are flanged, and whose lower edges extend beyond the concave face of the body, substantially as set forth. 65

2. A cigar-mold whose upper matrix or plunger is composed of a wooden body incased by a curb-strip of sheet metal, whose lower edges extend beyond the concave face of the body, and whose upper edges are provided 70 with inturned flanges d, which occupy kerfs or grooves in the body, in the manner designated. 75

In testimony of which invention I hereunto set my hand.

NAPOLEON DU BRUL.
